UNITED STATES PATENT OFFICE.

IRA R. SELTZER, OF WATERBURY, CONNECTICUT, ASSIGNOR TO THE GORDON ELECTRIC MFG. CO., OF WATERVILLE, CONNECTICUT, A CORPORATION.

TWO-CIRCUIT OR THREE-HEAT PUSH-THROUGH SWITCH.

Application filed March 13, 1922. Serial No. 543,152.

To all whom it may concern:

Be it known that I, IRA R. SELTZER, a citizen of the United States, residing at Waterbury, in the county of New Haven and State of Connecticut, have invented a new and useful Improvement in Two-Circuit or Three-Heat Push-Through Switches; and I do hereby declare the following, when taken in connection with the accompanying drawings, and the characters of reference marked thereon, to be a full, clear, and exact description of the same, and which said drawings constitute part of this application, and represent in—

15 Fig. 1 a view in side elevation of a push-through switch embodying my invention.

Fig. 2 a plan view thereof.

Fig. 3 an enlarged plan view of the switch with the top cap removed.

20 Fig. 4 a reverse plan view with the bottom cap removed.

Fig. 5 a view in longitudinal section on the line 5—5 of Fig. 3, omitting the shell.

Fig. 6 a detached view in side elevation 25 of the switch-mechisms.

My invention relates to an improvement in that class of push-through switches known as two-circuit or three-heat switches, the object being to produce, at a low cost for 30 manufacture, a simple, reliable and compact switch constructed with particular reference to rendering the binding terminals accessible without removing the switch-housing or disassembling the switch-mechanisms.

35 With these ends in view, my invention consists in a two-circuit or three-heat push-through switch characterized by having its switch-mechanisms located in a plane transverse to the longitudinal axis of the fixture, or in the same circumferential line or transverse plane of the structure.

40 My invention further consists in certain details of construction and combinations of parts as will be hereinafter described and 45 particularly pointed out in the claims.

In carrying out my invention, as herein shown, I employ a one-piece, chambered, cylindrical, insulating body 10 having its 50 flat upper end or face formed with two corresponding switch-recesses 11 located on opposite sides of a central longitudinal plane of the body, these recesses being adapted in size to receive independently organized switch-mechanisms of approved construc-

tion adapted to be operated by push-through buttons 12, all located in the same transverse plane, or, in other words, circumferentially in line. The switch-mechanisms shown are of the familiar "rocker" type and may be generally designated by the numerals 13 and 13^a. The push-through buttons 12 aforesaid pass outward through clearance holes 14 formed in the said body 10, are located in the same transverse plane, and are tangential to the face of the block. The upper face of the block 10 is also formed, near its edge, with a recess 15 for the reception of the common terminal-plate 16 carrying the binding-screw 17. At a point diametrically opposite the said recess 15, the upper face of the block is formed with a recess 18 receiving a main-line terminal-plate 19 carrying a binding-screw 20. Under the construction described, the switches 13 and 13^a and the binding-screws 17 and 20 are fully exposed and, therefore, rendered accessible by the removal of the top cap 21 of the switch-housing, which comprises a tubular shell 22 within which the cylindrical body 10 snugly fits and a corresponding bottom cap 23, the caps 21 and 23 being removably connected with the shell in any approved manner.

The flat lower face of the block 10 is formed, as shown in Figure 4, with two corresponding recesses 24 located on opposite sides of the same central longitudinal plane of the block, and respectively receiving the contact-terminal plate 25 of the switch 13^a, and the corresponding plate 26 of the switch 13, the said plate 25 carrying a binding-screw 27 and the said plate 26 carrying a binding-screw 28. The plate 25 overlaps a terminal-strip 29 located in a groove 30 leading to the circuit-closing-and-breaking member 31 of the switch 13^a. On the other hand, the plate 26 overlaps the lower end of a terminal-strip 32 located in a groove 33 leading out of the recess 24 and extending through the periphery of the block to the upper face thereof, into position to make contact with the circuit-closing-and-breaking member 34 of the switch 13. The plate 25 and strip 29 are held together by a screw 35, while the plate 26 and the strip 32 are held together by a screw 36.

The lower face of the block 10 is also formed with a recess 37 receiving a line-

wire terminal-plate 38 carrying a binding-screw 39 connected by a long screw 40 with the line-wire terminal-plate 19 aforesaid.

When the cap 23 is removed, the binding-screws 27, 28 and 39 will be exposed and accessible without disturbing the shell 22, or either of the switch-mechanisms.

The two switch-mechanisms 13 and 13^a, or any substitutes therefor, will be wired in the usual manner of two-circuit or three-heat push-through switches, my invention not being concerned with the wiring or the specific construction of the switches, but rather with mounting them in the block so as to render all of their binding terminals accessible by removing the caps at the ends of the shell or housing without removing the same, or in any way disturbing either of the switch-mechanisms.

My construction also, by locating the switch-mechanisms and their push-buttons in the same transverse plane, and therefore in the same circumferential line, is much more compact than a structure in which the switches are located on opposite sides of a plane passing longitudinally through the block, requiring a bridge extending over the switch mechanisms, and so spanning the length of the block. In switches of the same character of the prior art, it has been necessary to entirely remove the housing of the block, and in some instances to dismember the switch-mechanisms for the purpose of wiring.

I claim:

1. In a two-circuit or three-heat push-

button switch, the combination with a cylindrical block having a plurality of terminal-plate recesses formed in its respective ends, of a cylindrical shell for the said block, removable caps for the respective ends of the said shell, two independent unitary push-button switches located in independent switch-recesses also formed in the upper end of the block, and binding-terminals located in recesses in the respective ends of the block, whereby the said switches and all of the said binding terminals are exposed by the removal of the said caps without disturbing the shell or the said switches.

2. In a two-circuit or three-heat push-button switch, the combination with a cylindrical plug the upper end of which is formed with two switch-recesses located on opposite sides of its center, and two terminal-plate recesses, and the lower end of which is formed with three terminal-plate recesses; of a cylindrical-shell for the said block, removable caps for the respective ends of the said shell, two binding-terminals respectively located in the two terminal-plate recesses in the upper end of the block, two unitary switch-mechanisms respectively located in the said switch-recesses in the upper end of the block, and three binding-terminals respectively located in the three recesses in the lower end of the block, whereby, by removing the said caps, the said switches and all of the said binding-terminals are rendered accessible without removing the said shell or disturbing the said switch-mechanisms.

IRA R. SELTZER.
